UNITED STATES PATENT OFFICE

155,488

DESIGN FOR A PURSE LIGHT

John W. Crockett, Buffalo, N. Y.

Application May 27, 1949, Serial No. 2,921

Term of patent 3½ years

(Cl. D48—24)

To all whom it may concern:

Be it known that I, John W. Crockett, a citizen of the United States, residing at Buffalo, in the county of Erie and State of New York, have invented a new, original, and ornamental Design for a Purse Light, of which the following is a specification, reference being had to the accompanying drawings, forming part thereof.

In these figures:

Fig. 1 is a perspective view of a purse light embodying my new design.

Fig. 2 is a front elevational view thereof.

Fig. 3 is a top plan view thereof.

Fig. 4 is a bottom elevational view thereof.

Fig. 5 is a rear elevational view thereof.

Fig. 6 is a left end elevational view of the purse light shown in Fig. 2.

Fig. 7 is a right end elevational view thereof.

I claim:

The ornamental design for a purse light, substantially as shown.

JOHN W. CROCKETT.
